(57) **CLAIM**

The ornamental design for a skimmer lid with solar power water level control, as shown and described.

DESCRIPTION

FIG. 1 is a perspective view from above of a skimmer lid with solar power water level control;

FIG. 2 is a perspective view from below of the invention;

FIG. 3 is a top plan view of the invention;

FIG. 4 is a front elevation view of the invention the rear elevation view being a mirror image;

FIG. 5 is a right side view of the invention, the left side view being a mirror image; and,

FIG. 6 is a bottom plan view of the invention.

In the drawings, the broken lines illustrate features that form no part of the claimed design.
